KICKER FOR TOY BOATS

Frank L. Lindstrom, Bridgeport, Conn.

Application March 8, 1934, Serial No. 714,576

3 Claims. (Cl. 46—37)

This invention relates to new and useful improvements in toys and has particular relation to kickers for toy boats.

The objects and advantages of the invention will be made clear by a consideration of the following detailed description taken in connection with the accompanying drawing wherein a satisfactory embodiment of the invention is shown. However, it is to be understood that the invention is not limited to the details disclosed but includes all such variations and modifications as fall within the spirit of the invention and the scope of the appended claims.

In the drawing:

Fig. 1 is a sectional view taken substantially along the plane of the line 1—1 of Fig. 2;

Fig. 2 is a rear elevational view of the kicker; and

Fig. 3 is a front elevation view thereof.

Referring in detail to the drawing, a portion of a toy boat is generally designated 5 and a kicker for driving said boat is generally designated 6. This kicker comprises a mounting frame 7 shown as made up of three pieces or sections 8, 9 and 10. Sections 8 and 9 are arranged horizontally in vertically spaced relation and section 10 is arranged vertically and at their rear ends the sections 8 and 9 carry ears or lugs 11 which are passed through the section 10 and then turned against it. Also, the upper end of section 10 is bent inwardly at 12 to lie against the upper surface of the rear end portion of section 8 which end portion carries ears or lugs 13 bent over against the upper surface of the inturned portion 12 of section 10.

At its forward end, section 8 is turned downwardly providing a portion 14 and the forward end of section 9 is turned upwardly at 15. From Fig. 1 it will be clear that the extreme lower end of the down-turned portion 14 of section 8 rests against the lower surface of section 9. A circular casing 16 encloses sections 8 and 9 for the greater portions of their lengths and the section 8 carries a pair of ears 17 which extend through the upper wall of said casing and the casing carries a lug 18 bent against the forward under side of section 9 whereby the forward portions of sections 8 and 9 are clamped between said lug and the top wall of the casing.

The lower end portion of section 10 is bent to extend rearwardly as at 19 and then upwardly as at 20 providing a U-shaped bearing mounting a propeller shaft 21 which at its outer or rear end carries a propeller 22. Shaft 21 at the inner side of section 10 carries a pinion 23 which

pinion is in mesh with a gear 24 carried by a vertically extending shaft 25. Shaft 25 adjacent the gear 24 has bearing in a lug 26 lanced and pressed from the section 10 and the shaft also extends through and has bearing in the frame sections 8 and 9 and at its upper end carries a wheel 27. Obviously, as the shaft 25 is rotated the propeller 22 will be rotated.

A coil spring 28 is located within the casing 16 between the mounting frame sections 8 and 9 and the inner end of this spring is connected as at 29 to a winding key 30 which key extends through the casing and the parallel frame sections and includes a hand piece 31. The outer end of the spring 28 is in any suitable manner anchored to the downturned portion 14 of the frame section 8 as shown at 32. On turning of the key 30 in the proper direction the spring 28 will be wound and as it unwinds it will rotate the key. Secured to the key below the spring 28 is a relatively large gear 33 which gear meshes with a relatively small pinion 34 rigid with a shaft 35 mounted by the frame sections 8 and 9. Also, on the shaft 35 is a gear 36 meshing with a small diameter pinion 37 on the shaft 25.

From the foregoing, it will be clear that the frame 7 mounts a propeller and a spring motor and that the motor is geared to the propeller to drive the same as the spring of the motor unwinds. On the boat 5 there is secured a clip 38 having inturned edges 39 providing grooves. Frame section 9 carries a pair of outwardly directed flanges 40 and the kicker 6 may be readily attached to the boat 5 by relative movement between the kicker and boat to slide the flanges 40 into the grooves provided by the in-turned edges 39 of the clip 38.

With the means thus far described it will be noted that whenever the spring 28 unwinds it drives the propeller and it will be appreciated that while the key 30 is being operated to wind the spring 28 there is no means to prevent operation of the propeller or to prevent unwinding of the spring each time the key is given a partial turn and while it is released to enable the operator to take another grip on the key to further wind it. Also, if the spring is wound while the kicker is disconnected from the boat the spring will be run down by the time the kicker is mounted on the boat.

To prevent unwinding of the spring motor except when it is desired that the same unwind and drive the propeller 22, I provide a stop in the form of a lever 41 which lever is pivoted to the frame section 10 at 42. The upper portion 43

of the lever 41 is bent to clear the wheel 27 and such upper portion forms or is shaped to provide a handle. The extreme lower end of lever 41 is bent to provide a rearwardly extending portion or foot 44 capable of being moved into the path of movement of the propeller 22.

When the lever is positioned as best shown in Fig. 2 its foot piece 44 is disposed between a pair of the blades of the propeller 22 and so effectively prevents rotation of the propeller. Since the propeller cannot rotate and is geared to the spring motor it will be appreciated that such motor is prevented from unwinding or running down. On the handle portion of lever 41 being moved outwardly or toward the left in Fig. 2 the foot portion 44 of the lever will be carried into a position out of the path of movement of the propeller. A projection 45 on the frame section 10 limits swinging movement of the lever 41. It will now be clear that the entire kicker including the stop lever 41 is in the nature of a single unit easily applied to or removed from a boat. Lever 41 being on the frame 1 no special mounting means need be provided for it on the boat.

Having thus set forth the nature of my invention, what I claim is:

1. In a kicker for a toy boat, a mounting frame comprising a pair of horizontal spaced frame sections, a vertical frame section secured adjacent its upper end to the rear ends of said horizontal frame sections and holding them in spaced relation at their rear ends, one of said horizontal sections having its forward end turned to abut the other of said sections, a casing enclosing the forward portions of said sections, said casing including a lug engaging the forward portion of one of said sections to secure the said portions of the sections between the lug and the top wall of the

casing, a spring motor mounted by and located between said horizontal sections, a propeller mounted on the vertical section, and a driving connection between the motor and propeller.

2. In a kicker for a toy boat, a mounting frame, a spring motor on said frame, said frame including a substantially vertical portion extending downwardly of said spring motor, a propeller on said portion below the motor, a driving connection between the motor and propeller whereby as the motor unwinds it drives the propeller, a substantially vertically extending lever, means pivoting said lever to the rear side of said frame portion, said lever having its upper portion extending above the motor for convenient manipulation, and said lever extending to the propeller having its lower end angularly disposed whereby as the lever is rocked about its pivot its lower end may be brought into engagement with an edge of a blade of the propeller and secure the latter against rotation by the motor.

3. In combination, a boat body, a kicker comprising a mounting frame including a substantially horizontal and a substantially vertical portion at the rear of said horizontal portion, a spring motor mounted on said substantially horizontal portion, a propeller mounted on said substantially vertical portion, a driving connection between the motor and propeller whereby as the motor unwinds it drives the propeller, and complementary means on the upper side of the boat at the rear thereof and the lower side of the horizontal frame portion for mounting the frame on the boat with the vertical frame portion at the rear of the boat but with the motor over the boat.

FRANK L. LINDSTROM.
